Edward Little
INVENTOR
BY *Victor J. Evans*
ATTORNEY

UNITED STATES PATENT OFFICE.

EDWARD LITTLE, OF CUTLER, CALIFORNIA.

VALVE-GRINDING ATTACHMENT.

Application filed April 12, 1922. Serial No. 552,031.

To all whom it may concern:

Be it known that I, EDWARD LITTLE, a citizen of the United States, residing at Cutler, in the county of Tulare and State of California, have invented new and useful Improvements in Valve-Grinding Attachments, of which the following is a specification.

This invention relates to valve grinders, particularly to grinding devices designed for association with and to be mounted upon the cylinder block of an automobile engine and operable whereby to grind the last valve which generally is in a very inaccessible position so that it cannot be reached by means of the ordinary valve grinding tool.

An important object is the provision of a gear driven device of this character which includes a support which is longitudinally 20 adjustably mounted upon a base which is bolted onto the cylinder block, the arrangement being such that the support when in different adjusted positions will facilitate reaching the various valves without unbolt- 25 ing the base.

A further object is the provision of a valve grinding attachment of this character which will permit a rocking action of the support during the grinding operation so 30 that the valves may be permitted to rise upwardly from their seats a slight distance as is preferred in actual practice in order to avoid grooving the valve.

An additional object is the provision of a 35 device of this character which will be simple and inexpensive in manufacture, rapid and labor saving in action, positive and durable in service and a general improvement in the art.

With the above and other objects and advantages in view, the invention consists in the details of construction to be hereinafter more fully described and claimed, and illustrated in the accompanying drawings,

45 wherein:—

Figure 1 is a plan view of my device showing it in operative position upon a cylinder block.

Figure 2 is a side elevation thereof.

50 Figure 3 is a side elevation showing a different adjustment a portion of the engine being in section,

Figure 4 is a longitudinal section through the device,

55 Figure 5 is a bottom plan view of the supporting member,

Figure 6 is a perspective view of the attaching member,

Figure 7 is a fragmentary perspective view of the base or supporting member, 60

Figure 8 is a detail perspective view of one of the gears, the outer portion thereof being broken away, the view illustrating the means for attaching the operating handle and

65 Figure 9 is a detail perspective view with parts broken away, showing the valve engaging member.

Referring more particularly to the drawings the letter A indicates the cylinder block 70 of an engine, and B designates the valves therein to be ground. In carrying out my invention, I provide a device which includes a base 10 which may be constructed of sheet metal or as a casting and which includes an 75 attaching portion 11 of plate like form provided with holes 12 for the passage of two of the securing bolts C which ordinarily hold the cylinder heads in position. This base member further includes an upstanding 80 portion 13 which is formed at its corners with lugs 14 for a purpose to be described.

Designed for association with this base is an elongated supporting plate 15 which is provided at spaced points with transverse 85 grooves 16 which are designed to be engaged upon the projecting lugs 14 of the base member for the purpose of holding the supporting plate at any desired adjusted position with respect to the cylinder block. 90 It is to be observed that the provision of the grooves 16 will permit the supporting plate to have a rocking action upon the base for a purpose to be described. This supporting plate member 15 is provided at 95 spaced intervals with bearing holes 17, 18 and 19 within the first of which, namely 17, is journaled the shaft 20 of a gear 21 which meshes with a similar gear 22 which has its shaft 23 journaled in the hole 18. The gear 100 22 in turn meshes with a similar gear 24 which has its shaft 25 journaled in the hole 19. It is intended that the gear 21 be incapable of removal from the plate 15 and to this end the shaft 20 is prevented from 105 longitudinal removal from the plate by means of a suitable transverse pin 26 or the like. The gear 22 and 24 may be freely removed if such is desired for a purpose to be described. The shaft 20 is formed at the 110 underside of the plate 15 with a transverse groove 27 within which may be disposed a

valve grinding tool 28 of conventional formation but which is here shown as being of plate-like form with tits or lugs 29 designed to be engaged within grooves provided in the top of a valve head. The shaft members 23 and 25 are likewise provided at one end with similar grooves 30 and 31 respectively within which may be engaged similar valve tools, that is similar to the 10 valve tool 28, while the other end of the shaft members 23 and 25 are formed for connection with any suitable tool indicated at 32 for effecting rotary movement.

Assuming that the device has been constructed and assembled as above described, the operation is as follows: The base member 10 is of course bolted onto the cylinder block by means of the bolt C and the plate member 15 is disposed with the desired one 15 of the grooves 16 in engagement with lugs 14 on the base member. The different gears are placed with their shaft in the holes 17, 18 and 19 and rotary movement is imparted to the endmost gear 24 by means of the 20 handle device shown. This movement will be communicated to both of the other gears 21 and 22 so that they will both be rotated and will carry with them whatever valve grinding tools 28 are associated with them. 25 If desired the valve grinding tool may be associated with each gear, although it may be associated with only the endmost gear 21 so as to facilitate grinding of a valve which is generally the last one which is ordinarily hard to reach. In this way it will be seen that by means of this device three valves may be ground simultaneously, or any tool or any one alone. When it is desired to project the bearing 16 under the 30 cowl of the automobile within which the engine is located, it is of course necessary that the endmost groove 16 most remote from the engine be the one engaged upon the lugs 14 of the base member. It is also to be observed that there is a capability of rocking 35 action of the plate member 15 upon the base so as to permit unseating of the valves while they are being ground as is the general practice in order to prevent grooving of the 40 valves and their seats by continuous rotary movement without interruption.

From the foregoing description and a

study of the drawings it will be apparent that I have thus provided a simply constructed and consequently inexpensive valve 55 grinding device which will be highly advantageous and time saving especially for reaching valves which are ordinarily inaccessible or difficult of access. Owing to the simplicity of the construction and the fewness of the parts, it will be apparent that the device will not only be inexpensive to manufacture, but will be not likely to get out of order so that it should have a long life and satisfactorily perform all the functions for 60 65 which it is intended.

While I have shown and described the preferred embodiment of the invention, it is of course to be understood that I reserve the right to make such changes in the form, construction and arrangement of parts as will not depart from the spirit of the invention or the scope of the subjoined claims.

What is claimed is:

1. A device of the character described 75 comprising a base member designed to be secured upon the block of an engine, and formed with an upstanding portion, an elongated plate member detachably and adjustably engaged upon the upstanding portion of the base member, a series of gears journaled upon said elongated plate member, means for imparting rotation to one of the endmost gears, and a plurality of valve grinding members associated with the respective gears.

2. A device of the character described comprising a base member designed to be secured upon the block of an engine, and formed with an upstanding portion, an elongated plate member detachably and adjustably engaged upon the upstanding portion of the base member, a series of gears journaled upon said elongated plate member, means for imparting rotation to one of the endmost gears, and a plurality of valve grinding members associated with the respective gears, said member being formed with a plurality of transverse grooves selectively engageable upon the upstanding 100 portion of the base member.

In testimony whereof I affix my signature.

EDWARD LITTLE.
